UNITED STATES PATENT OFFICE.

HENRY C. EGERTON, OF RIDGEWOOD, NEW JERSEY.

RUBBER SHOE-SOLE FOR TURN-SHOES.

1,352,736.

Specification of Letters Patent. Patented Sept. 14, 1920.

Application filed December 2, 1918. Serial No. 264,935.

To all whom it may concern:

Be it known that I, HENRY C. EGERTON, a citizen of the United States, and resident of Ridgewood, county of Bergen, State of New Jersey, have made a certain new and useful Invention Relating to Rubber Shoe-Soles for Turn-Shoes, of which the following is a specification taken in connection with the accompanying drawing.

- 10 This invention relates especially to rubber or other composition soles adapted for turned shoes or the like in which a sewing flap of fabric, which may advantageously be strengthened by more or less coating or 15 impregnating it with rubber or other suitable somewhat flexible strengthening material, and which may also if desired be folded, doubled or reinforced to have the desired strength and thickness, is cemented 20 or vulcanized to the rubber shoe sole and held in position thereon preferably in connection with stiffening fabric or fibrous elements, which may contain phenolic condensation cementing and stiffening material 25 and be held in position upon the sewing flap layers or members. This sewing flap member may, if desired, extend beneath the canvas or other fibrous stiffener layers throughout their entire extent, and may be 30 rubberized on the side adjacent the rubber sole so as to act as a connector fabric or member promoting the union of these parts. When the upper has been stitched to this 35 sewing flap in the usual way the sewing flap may be turned inward and more or less contained in a seam recess formed in the shoe sole adjacent the sewing flap; and by forcing or hammering the seam into this recess a more nearly flush joint may be obtained, which may of course be still further 40 covered by an insole which may be inserted thereover after the shoe upper has been turned and finished in the usual way.

In the accompanying drawing showing 45 in a somewhat diagrammatic way various illustrative embodiments of the invention,

Figure 1 is a perspective view partly in section showing portions of a shoe sole and related members.

50 Fig. 2 is a corresponding sectional view showing the parts in separated position for greater clearness.

Fig. 3 is a sectional view through the assembling and molding apparatus for 55 forming such a shoe sole.

Fig. 4 is a sectional view showing another arrangement with the parts in separated position; and

Fig. 5 is a sectional view through still another arrangement of shoe sole elements 60 indicated in separated position in connection with a mold adapted for uniting and vulcanizing them.

The shoe soles which may, if desired, include integral heels in some cases may be of 65 any suitable rubber or other composition and in the case of a vulcanized rubber shoe sole 1 the rubber composition may be selected with particular reference to its gripping and wearing qualities while the desired stiffness may be secured through the incorporation of additional stiffening layers or elements. Several layers or members 3 of fabric, paper or other fibrous material, such as 70 cotton fiber, cotton batting, paper pulp, etc. 75 or mixtures thereof, may be used for this purpose and may be coated or preferably quite thoroughly impregnated with suitable phenolic condensation cementing material, such, for instance, as bakelite, condensite or redmanol varnish compositions. Two layers of 8 oz. canvas thoroughly impregnated with bakelite varnish and dried may under pressure be cemented and united together to form a strong and stiff member or 80 stiffening sheet about a 16th of an inch thick which may give ample stiffness to the rubber shoe sole. As indicated in Figs. 1 to 3 these stiffener members 3 preferably do not extend to the edges of the shoe sole 1 but are 85 arranged a sixteenth of an inch or an eighth of an inch inside of these edges so that projecting edge portions 2 are left around the sole to give the finished shoe a more desirable appearance. A connector member 4 of 90 canvas or other suitable fabric may advantageously be interposed between the stiffener members and the rubber sole and may be formed with reinforced or doubled edge 95 portions projecting beyond the stiffener so as to serve as a sewing flap to which the upper of the turned shoe may be attached. The connector fabric may advantageously 100 in most cases be formed with a frictioned or other rubber coating 10 on the side adjacent the rubber sole and the edge portions of this connector member may be doubled back upon themselves so as to form a doubled edge 12 adjacent the edge of the shoe sole, this part of the connector then being 110

carried inward to a sufficient extent to secure ample connection with the other parts of the shoe sole, and if desired, this connector member may be turned back on itself 5 at about the point 13 and its edges carried outward to about the point 12, the rubberized face of this fabric engaging the rubberized face of the adjacent fold thereof and leaving a relatively uncoated exposed 10 surface to more securely and strongly unite with the phenolic condensation cementing material of the stiffener members. In some cases the fabric may be cut or gored around the curved toe and heel portions of the connector member so as to minimize undesirably doubled portions and make the sewing flap of more uniform thickness at these parts, although such additional thicknesses of the fabric are not in all cases objectionable where ample rubber has been incorporated 15 in the fabric by the original coating or otherwise during the forming of this element. This fabric layer may of course be folded up and compressed at its doubled portions so as to secure the adhesion thereof so that a shaped piece is secured which may be more readily assembled with the other elements in molding the sole. As shown in Fig. 3 the sole may be molded and vulcanized 20 advantageously by laying the coated and dried stiffener members 3 in the mold section 15 preferably after they have been somewhat heated to facilitate bending and then the connector sewing flap member 4 may be 25 put in place upon them and properly centered by the use of any desired means such as locating pins or the like to insure the proper positioning of these parts, then another coöperating mold element may be put 30 in place on the bottom mold 15 so as to bend down and hold the sewing flap. This may be effected conveniently by having a multiple or one-piece mold element 20 adapted to coöperate with the bottom mold 15 and 35 positioned with respect thereto by the pins 18 which may have the tapered upper ends 19 coöoperating with holes 20 in this upper mold section. This mold section 20 may have a retainer flange 50 on its inner edge 40 which is adapted to force the sewing flap 5 downward and inward into engagement with the gripping rim 16 on the lower mold section so as to clamp it between these parts when the locking or securing hooks 38 are 45 snapped over the coöperating pins to lock the mold sections together. The sewing flap may thus be definitely and securely held in 50 position and more or less shaped up at the same time during the molding and vulcanizing 55 of the sole. This mold section may also, if desired, be formed with a recess 22 corresponding to the edge 2 of the shoe sole, the outline of which is of course defined by the face 23 of this mold section. The vulcanizable rubber blank 1 which may be more or 60 less profiled or shaped up may then be put in place in the mold and forced into contact with the other elements therein by the top mold section, such as 25, which may in some cases be advantageously provided with the 70 holes 26 coöperating with the alining pins 19. The mold may then be heated in any desired way while under pressure so that the vulcanizing heat and pressure is secured which simultaneously unites the elements 75 and cures the phenolic condensation cementing material in the stiffener members so that all the parts are securely and permanently united to form a unitary sole. A heat of 250° to 320° Fahrenheit for half an hour or 80 an hour more or less is usually sufficient for this purpose, depending, of course, upon the rubber composition employed and the particular phenolic condensation cementing material used in connection therewith. 85

The upper members 7 which may have the seam portions 6 may of course be sewed to the sewing flaps 5 in any suitable machine which preferably somewhat compresses the edge portions 2 of the rubber shoe sole 90 while this sewing is taking place so as to make a better and neater joint. The line of this stitching 8 is indicated in Fig. 1 and when this sewing is completed the seam may be turned over so that the seam members are 95 bent or folded more or less into the seam recess 9 which may be formed around the sole adjacent the sewing flap as by forming a suitable projection 17 around the mold section for this purpose. The seam members 100 may of course be hammered or forced into this recess and covered by an insole applied or cemented in place, suitable phenolic condensation cementing compositions being desirable where the stiffener members 3 are 105 exposed on the inner side of the sole. If desired, however, a rubberized facing layer, such as 14, indicated in Fig. 2 may in some cases be applied to the stiffener layers and cemented thereto during the molding operation so as to leave the frictioned or other rubber coating 10 exposed on the inside of the shoe sole to facilitate the cementing of an insole thereto by rubber cementing compositions after the upper has been sewed to the 110 sole. 115

Fig. 4 shows another arrangement in which the rubber or other composition shoe sole 27 is indicated as having substantially uniform thickness throughout. The connector sewing flap member 4 of fabric may be folded upon itself so as to form the fold 12, the edge portion extending back to about the point 13 and additional reinforcing fabric or strips may be incorporated in this 120 edge portion 29 to form a sewing flap of the desired strength and thickness. If desired, the edges of the connector member may be folded outward to form the portion 11 which may on its exposed side be rela- 125 130

tively free from any rubberized coating so as to facilitate cementing union with the one or more stiffener members or fabric or fibrous layers 3 molded thereto. As indicated in this case one or more fabric layers may be inserted within the edge fold 12 of such a connector member and this reinforcing fabric 28 which may be a heavy woven or braided tape or the like may be 10 rubberized on both sides before being put in place so as to more effectively unite it to the other adjacent fabric portions. Such a connector sewing flap member may of course be folded and temporarily cemented or 15 united and then assembled with the other parts and vulcanized and cemented together in the same general way as indicated in connection with the Fig. 3 construction.

Fig. 5 shows still another arrangement 20 in which the sewing flap may comprise one or more braided cords, such as 31, which may advantageously be inclosed within and secured to the edge loops 32 of the connector fabric. This may be readily accomplished 25 by using a strip or layer 30 of light canvas or other suitable fabric which has been given a frictioned or other rubber coating on one side and applying it to the one or more stiffener members or fabric layers 3 30 which may be previously inserted in the mold 34 and positioned therein as by the locating pins 37 which may in some cases be withdrawn after the mold is closed or during the vulcanizing operation, if desired, so 35 as to allow the holes to close during the molding operation. This connector fabric 30 may then be put in place and its edge portions 31 forced into the grooves 35 in the mold and then the braided cord 32 may be 40 forced into these grooves and the edge portions 33 of the connector fabric may be brought back above the stiffener layers 3 so as to be carried in some cases to or adjacent the center portions of the shoe sole. In 45 some cases it is desirable to use an additional layer of connector fabric 39 which may advantageously be coated or frictioned with rubber on both sides so as to securely unite with the connector layer and also 50 with the rubber sole composition blank 27 which may be forced into place and vulcanized or united to the other parts when the top mold section 36 is forced home and the mold heated for the desired time.

This invention has been described in connection with a number of illustrative embodiments, forms, proportions, elements, parts, shapes, materials, compositions, methods of preparation, production and use, to 55 the details of which disclosure the invention is not of course to be limited, since what is claimed as new and what is desired to be secured by Letters Patent is set forth in the appended claims:

1. The integral rubber shoe sole for turn

shoes and the like which comprises a vulcanized rubber composition sole, a rubberized fabric sewing flap member engaging and united to said sole and forming a rubberized fabric sewing flap which is adapted to be 70 sewed to the shoe upper and a fibrous sole stiffener member carrying cured phenolic condensation cementing and stiffening material cemented to said sewing flap member so as to leave its edges projecting beyond the edges 75 of said stiffener member.

2. The integral rubber shoe sole for turn 80 shoes and the like which comprises a sole, a rubberized fabric connector and sewing flap member united to said sole and having a reinforced multiple thickness edge portion forming a fabric sewing flap which is adapted to be sewed to the shoe upper, a fabric stiffener member carrying cured phenolic condensation cementing and stiffening 85 material cemented to said connector member so as to leave the sewing flap projecting beyond the edges of said stiffener member, said sole being formed with a seam recess adjacent said sewing flap to accommodate 90 the sewing flap seam portions after the upper has been sewed thereto.

3. The integral rubber shoe sole for turn 95 shoes and the like which comprises a sole, a rubberized fabric connector and sewing flap member united to said sole and having a reinforced multiple thickness edge portion forming a fabric sewing flap which is adapted to be sewed to the shoe upper and a fabric stiffener member carrying cured phenolic condensation cementing and stiffening 100 material cemented to said connector member so as to leave the sewing flap projecting beyond the edges of said stiffener member.

4. The integral rubber shoe sole for turn 105 shoes and the like which comprises a sole, a fabric sewing flap member united to said sole and having a reinforced multiple thickness edge portion forming a fabric sewing flap which is adapted to be sewed to the shoe upper and a fabric stiffener member carrying cured phenolic condensation stiffening 110 material secured to said sewing flap member so as to leave its edges projecting 115 beyond the edges of said stiffener member.

5. The shoe sole for turn shoes and the like which comprises a sole, a fabric sewing flap member united to said sole and forming a fabric sewing flap which is adapted to be 120 sewed to the shoe upper and a fabric stiffener member carrying cured phenolic condensation stiffening material secured to said sewing flap member.

6. The integral shoe sole for turn shoes 125 and the like which comprises a rubber composition sole, a rubberized sewing flap member united to said sole and forming a fabric sewing flap to which the shoe upper is adapted to be sewed, and a fabric stiffener 130

member carrying cured phenolic condensation stiffening material cemented to said sewing flap member to support and strengthen said sewing flap.

5 7. The shoe sole for turn shoes and the like which comprises a composition sole, a reinforced fibrous sewing flap member united to said sole and forming a sewing

flap to which the shoe upper is adapted to be sewed, and a fibrous securing member 10 carrying cured phenolic condensation stiffening material secured to said sewing flap member to support and strengthen said sewing flap.

HENRY C. EGERTON.
